DESIGN FOR A HAIR ROLL

John W. W. Holden, Providence, R. I.

Application May 27, 1941, Serial No. 101,171

Term of patent 7 years

To all whom it may concern:

Be it known that I, John W. W. Holden, a citizen of the United States, residing at Providence, in the county of Providence and State of Rhode Island, have invented a new, original, and ornamental Design for a Hair Roll, of which the following is a specification, reference being had to the accompanying drawing, constituting a part thereof.

Fig. 1 is a side elevational view of a hair roll showing my new design;

Fig. 2 is an end elevational view thereof;

Fig. 3 is an enlarged fragmentary detailed view of a portion of the roll shown in Fig. 1.

I claim:

The ornamental design for a hair roll, substantially as shown.

JOHN W. W. HOLDEN.
